UNITED STATES PATENT OFFICE.

WILLIAM KNY, OF KINGSWINFORD, NEAR DUDLEY, ENGLAND.

DESIGN FOR A GOBLET.

40,360.

Specification for Design.

Patented Nov. 16, 1909.

Application filed May 17, 1909. Serial No. 496,670. Term of patent 7 years.

To all whom it may concern:

Be it known that I, WILLIAM KNY, a subject of the King of Great Britain, residing at Kingswinford, near Dudley, in the county of Stafford and Kingdom of England, have invented a new, original, and ornamental Design for Goblets; and I do hereby declare the following to be a full, clear, and exact description of the same, reference being had to the accompanying drawing, forming a part thereof.

As shown in the drawing the ornamental design is a goblet supported upon a foot 1 with a stem 2 having bilge 3 and constriction 4. Above the stem the goblet rises in a swell as at 5 reversely curved to form an outwardly flaring lip 6. About the goblet beneath the lip 6 a row of ornamental figures is produced consisting of a conventional blossom 7 with calyx 8 and pistils 9. Below the border of blossoms a row of spaced

circles 10 is disposed, alternate circles being connected by straight lines 11 extending longitudinally of the goblet to the stem. Between the straight lines 11 other circles 12 are disposed with straight lines 13 connecting the circles 10 therewith and extended lines 14 connecting the circles 12 with the stem. The blossom and calyxes referred to are provided with a background frosted or otherwise rendered semi-opaque to give the effect of body or substance. The goblet, and stem, are both circular in cross-section and the foot 1 also circular.

I claim—

The ornamental design for a goblet as shown and described.

WILLIAM KNY.
